UNITED STATES PATENT OFFICE.

GEORGE A. NELSON, OF CHICAGO, ILLINOIS, ASSIGNOR TO HOLTON & HILDRETH, OF SAME PLACE.

ROCKING-CHAIR.

SPECIFICATION forming part of Letters Patent No. 244,021, dated July 5, 1881.
Application filed March 25, 1881. (No model.)

To all whom it may concern:

Be it known that I, GEORGE A. NELSON, of Chicago, in the county of Cook and State of Illinois, have invented certain new and useful

5 Improvements in Rocking-Chairs; and I do hereby declare the following to be a full, clear, and exact description thereof, that will enable others to make and use the same, reference being had to the accompanying drawings, and 10 to letters of reference marked thereon, forming a part of this specification.

This invention relates to that class of rocking-chairs in which the rocking members rest upon a base or supporting-frame, to which 15 they are secured by a double C-shaped spring, so constructed and arranged as to permit of a long, smooth sweep of the rockers and an equal division of the strain between the parts to which the spring is attached.

20 Figure 1 is a vertical transverse section of the rocking members and supporting-base, showing the position of the spring when the rockers are at rest. Fig. 2 is a view of the same, showing the relative action of the spring 25 when the rockers are moved in either direction; and Fig. 3, a side elevation of one of the rockers and support, looking outward from the line 3 3, Fig. 1.

Referring to the drawings, A represents a 30 double C-shaped spring, consisting of the upper bow, A', and the lower bow, A², and having the lateral projecting arms B B' formed integral therewith. C represents the rocking members, and C' the supporting-base for the 35 same. The extreme ends of the spring-arms B B' are turned at right angles from each other to form the bearing-flanges a a'. The ends B of the upper half of the spring are attached to the rockers C, and the ends B' of the lower 40 half of the spring are attached to the base c' on a vertical line through the center of the chair. At the point where the arms B B' join the body of the spring proper they are riveted together, having a block of leather, a², or other 45 suitable material interposed, to prevent the

parts from being too rigid and to retain the upper and lower sections of the spring in proper position relative to each other.

When the rockers are moved either backward or forward the projecting arms of the 50 spring have a vertical movement, and spread out in the manner illustrated in Fig. 2 of the drawings. At the same time the body of the spring has a lateral adjustment, the upper and lower parts of the spring flattening in the direction of each other, thereby readily accommodating itself to the movements of the rockers, imparting an easy and smooth action to the extreme points of the rockers, and entirely obviating the irregular action of the parts, 60 which always has been a very uncomfortable and objectionable feature in this class of chairs. 55

What I claim, and desire to secure by Letters Patent, is—

1. In a rocking-chair, the double C-shaped 65 spring A, formed in two distinct parts, consisting of the upper half or section, A', and the lower half, A², arranged one above the other to form the body of the spring proper, and having the lateral projecting arms B B' formed 70 integral therewith, said arms being riveted together at their junction with the body of the spring A, while the outer ends of said arms are bent at right angles from each other and attached to the rocking members and the supporting-base in their relative position, substantially as herein shown and described. 75

2. In a spring attachment for rocking-chairs, the combination, with the rocking members C and the supporting-base C', of the double C-shaped 80 spring A, consisting of the duplicate parts or sections A' A², arranged in a vertical plane relative to each other and provided with the lateral attaching-arms B B', all constructed, arranged, and operating as set forth.

GEORGE A. NELSON.
